(57) **CLAIM**

The ornamental design for an art drying rack as shown and described.

DESCRIPTION

FIG. 1 is a top perspective view of the art drying rack;
FIG. 2 is a front view thereof;
FIG. 3 is a back view thereof;
FIG. 4 is a right side view thereof;
FIG. 5 is a left side view thereof;
FIG. 6 is top view thereof;
FIG. 7 is a bottom view thereof;
FIG. 8 is a perspective view of another embodiment of the art drying rack;
FIG. 9 is a front view thereof;
FIG. 10 is a back view thereof;
FIG. 11 is a right side view thereof;
FIG. 12 is a left side view thereof;
FIG. 13 is top view thereof;
FIG. 14 is a bottom view thereof;
FIG. 15 is a perspective view of a third embodiment of the art drying rack;
FIG. 16 is a front view thereof;
FIG. 17 is a back view thereof;
FIG. 18 is a right side view thereof;
FIG. 19 is a left side view thereof;
FIG. 20 is top view thereof; and,
FIG. 21 is a bottom view thereof.

The dashed lines in the drawings represent portions of the art drying rack which do not form part of the claimed design.

1 Claim, 21 Drawing Sheets
